VACUUM TUBE AMPLIFIER

Stuart Ballantine, Mountain Lakes, N. J., assignor, by mesne assignments, to Radio Corporation of America, New York, N. Y., a corporation of Delaware

Application March 31, 1930, Serial No. 440,514

21 Claims. (Cl. 250—20)

This invention relates to vacuum tube amplifiers and particularly to radio receivers employing radio frequency amplifiers.

An object of the invention is to provide a vacuum tube amplifier including an improved system for controlling the output level. A further object is to provide a vacuum tube amplifier including volume control apparatus effective to prevent distortion at high signal inputs and to preserve a maximum signal to noise ratio. More specifically, an object is to provide a vacuum tube amplifier in which the control of volume is effected by changing simultaneously the amplification of the vacuum tube amplifier and the magnitude of the signal voltage impressed upon the amplifier.

The novel features which I believe to be characteristic of my invention are set forth in particularity in the appended claims, the invention itself, however, as to both its organization and method of operation will best be understood by reference to the following description taken in connection with the drawings in which I have indicated diagrammatically one circuit organization whereby my invention may be carried into effect.

These and other objects will be apparent from the following specification when taken with the accompanying drawings in which:

Figs. 1 and 2 are curve sheets showing the variation of shot-noise with amplification, and

Fig. 3 is a circuit diagram of a radio receiver embodying the invention.

In conventional radio receivers, the control of volume or output level has been effected in one of two ways, i. e., the input voltage has been controlled by a voltage divider which was adjusted to impress any desired portion of the antenna voltage upon the first amplifier tube, or the full antenna voltage has been impressed upon the amplifier and the radio frequency amplification has been controlled by regulating the direct current potential applied to a tube element, for example, to the control grid. Both of these methods possess certain disadvantages.

In the first vacuum tube in the radio frequency amplifier there are natural statistical fluctuations in the electron flow between cathode and plate which, as pointed out by W. Schottky (Annalen der Physik, vol. 57, 541, 1918), cause characteristic oscillations in the tuned circuits associated with the tube. In practice these oscillations are ordinarily of such small amplitude as to be inaudible in the absence of an incoming signal, but when a carrier or signal is present,

they beat with this carrier and produce a noise in the loud-speaker or telephones. With a square-law detector, this noise is proportional to the carrier, or signal. The noise resembles the sound of escaping steam and is called "shot-effect noise" or briefly "shot-noise". Other causes of noises in tubes and circuits also exist, but for convenience they will all be referred to here as shot-noise.

Since the shot-noise is dependent upon the carrier voltage, it is evident that it will be constant regardless of the magnitude of the incoming signal wave so long as the input to the first amplifier is adjusted for a constant signal voltage (or constant carrier voltage) at the detector. The result of this is a constant signal to noise ratio in the reception of all stations whether local or distant when the volume is adjusted by means of antenna coupling. This constitutes a decided drawback of the method as will be seen presently.

Now turning to the other method, I have discovered experimentally that in general any adjustment of electrode voltages in a vacuum tube which reduces the amplification also reduces the noise in proportion. Experimental evidence of this in the case of an amplifier employing tetrodes is shown in the curves reproduced in Figs. 1 and 2. Fig. 1 shows this close relation between shot-noise and amplification when the control grid voltage is varied.

Curve A shows the relationship between the amplification and the control grid bias; the potentials applied to the other electrodes being constant. Curve B shows the relationship between shot-noise and control grid bias for the same amplifier. In Fig. 2, the curves C and D represent the variation of amplification and of shot-noise, respectively, with plate voltage. In all cases, the ratio of amplification to shot-noise remains approximately constant over the useful part of the control range. The significance of this is that in controlling for constant output, the signal remains constant while the shot-noise decreases continuously as the strength of the incoming wave increases, thus resulting in an improvement of the signal to noise ratio for local stations. It will be clear that from the viewpoint of noise production this method is superior to the other, the superiority increasing with the incoming signal strength. The method has, however, the disadvantage that as the voltage on the input of the amplifier tubes increases, a point is soon reached at which the relation between input and output

voltages becomes non-linear and distortion results.

I propose to retain the advantage of high signal noise ratio of the amplification control method, and to avoid the distortions which occur in this method when the signal voltage is large by employing a combination of the amplification control and input voltage control methods. This may be done by employing two controls, one of each type, the two controls being so related that, with increasing signal strengths, the antenna control prevents the input to the first amplifier tube from rising above the value which would produce distortion in the amplifier. It is preferable to simplify the receiver operation by linking these controls in such a way as to require but one knob for adjustment.

Referring to Fig. 3 which illustrates an application of the invention to a typical radio receiver, the reference numeral 1 identifies the voltage divider which determines the proportion of the antenna voltage which is applied to the first amplifier tube. The amplification of the first tube is controlled by the control grid bias which is determined by the voltage drop across that portion of the voltage divider 2 which is included between the contact arm 3 and the grounded side of the voltage divider 2. This contact arm 3 and the contact arm 4 of the antenna control are mounted upon a common operating shaft 5 which carries a knob 6 or other convenient adjusting means.

So far as concerns the present invention, the detailed construction of the radio receiver is not important and may follow any usual or desired design. The control of amplification may be confined to a single stage, as in the circuit shown in Fig. 3, or may include two or more stages. It is also to be understood that the amplification control may be obtained by varying the screen grid or the plate potential since, as shown by Figs. 1 and 2, a decrease in amplification reduces the shot-noise regardless of the particular operating potential which is adjusted to control the amplification.

It will be apparent that there is considerable latitude in the construction of amplifiers embodying the invention.

While I have indicated and described one arrangement for carrying my invention into effect, it will be apparent to one skilled in the art that my invention is by no means limited to the particular organization shown and described, but that many modifications may be made without departing from the scope of my invention as set forth in the appended claims.

I claim:

1. The method of controlling the output level of a vacuum tube amplifier and increasing the signal to noise ratio which comprises simultaneously adjusting the amplification of the amplifier and the magnitude of the signal voltage impressed upon the same.

2. In the operation of a radio receiver having a radio frequency amplifier, the method of increasing the range of signal wave voltages that may be transmitted without distortion, which comprises simultaneously reducing the proportion of the received signal voltage which is impressed upon the amplifier and the amplification of said amplifier.

3. In a carrier wave amplifier, the combination with means for adjusting the amplification of said amplifier, of means for adjusting the proportion of received signal voltage to amplifier

input voltage, and means for simultaneously adjusting the said input and amplification control means.

4. In a radio receiver, a voltage divider for determining the ratio of antenna voltage to amplifier input voltage, a voltage divider for determining the potential applied to a volume control element of the amplifier, and means linking the movable contacts of said voltage dividers to insure the simultaneous adjustment thereof. 10

5. In a radio receiver, a radio frequency amplifier, an antenna control for regulating the input from a collector structure to said amplifier, a control for adjusting an operating potential applied to said amplifier to control thereby the 15 amplification of said amplifier, and means linking said controls to reduce the input to said amplifier as the amplification thereof is reduced.

6. The combination with an electrical signal amplifier having an input circuit, an output circuit, and at least one electric discharge amplifier device connected between said circuits for the transmission of signals from said input to said output circuit, of means for varying the amplification of the amplifier device, means for varying 20 the signal strength applied to said input circuit, and additional means for varying said last named means simultaneously with said first named means.

7. The combination with an electrical signal 30 amplifier having an input circuit, an output circuit, and at least one electric discharge amplifier device, connected between said circuits for the transmission of signals from said input circuit to said output circuit, of means provided with an 35 element movable between certain limits to vary the transmission efficiency of said amplifier device, means for varying the signal strength applied to said input circuit, said last named means being operative to reduce the signal strength applied to the input circuit as the transmission 40 efficiency of the amplifier device is being reduced by said first named means, and a common means for operating said second named means simultaneously with said first named means. 45

8. The combination with an electrical signal amplifier having an input circuit, an output circuit and at least one electric discharge amplifier device connected between said circuits for the transmission of signals from said input to said output circuit, of means provided with an element movable between said limits to vary the transmission efficiency of said amplifier device, a variable resistor, said resistor having a movable element arranged to vary the signal strength applied to said input circuit, the movement of said last named element being effective to vary the signal strength as the transmission efficiency of the amplifier device is varied, and means connected with said movable elements for moving 60 the same simultaneously. 50

9. The combination with an electrical signal amplifier having an input circuit, an output circuit and at least one electric discharge amplifier device connected between said circuits for the 65 transmission of signals from said input to said output circuits, of means having a common control and provided with movable elements for simultaneously varying the transmission efficiency of said amplifier device and the strength of signals received by said input circuit. 70

10. The combination with an electrical signal amplifier having an input circuit, an output circuit and at least one electric discharge amplifier device connected between said circuits for the 75

- transmission of signals from said input to said output circuits, of simultaneously variable means to vary the transmission efficiency of said amplifier device and a signal voltage applied to said 5 input circuit, the range of movement of the transmission efficiency varying means at least equaling the range of control of the signal voltage varying means in a direction of movement to increase the transmission efficiency.
- 10 11. In the operation of radio receiving apparatus utilizing thermionic tubes for amplifying radio frequency signal energy, the method of effecting control of volume of reproduction, which comprises varying the transfer of radio frequency 10 signal energy between predetermined limits, and simultaneously varying the amplification characteristic of at least one of said tubes.
- 15 12. In the operation of radio receiving apparatus utilizing thermionic tubes for amplifying radio frequency signal energy, the method of reducing the volume of signals which comprises modifying the amplification characteristic of at least one of said tubes to decrease the amplification of signal energy, and simultaneously decreasing the transfer of signal energy.
- 20 13. In the operation of radio receiving apparatus utilizing thermionic tubes for amplifying radio frequency signal energy, the method of reducing amplitude of signals which comprises 20 varying the potential applied to a control electrode of at least one of said tubes and simultaneously decreasing signal energy transferred to the input of said one tube.
- 25 14. In the operation of radio receiving apparatus utilizing thermionic tubes of the screen grid type for amplifying radio frequency signal energy, the method of varying volume of signals which comprises varying the positive potential applied to the screen grid of at least one of said 25 tubes, and varying the signal energy transferred to the input of said one tube.
- 30 15. Radio receiving apparatus comprising at least one thermionic amplifier tube of the screen grid type, radio frequency input and output 30 circuits therefor, and a volume control element adjustable to vary both the positive biasing potential of the screen grid of said tube and the magnitude of transfer of signal energy to the input circuit thereof.
- 35 16. Radio receiving apparatus comprising a 35 screen grid amplifier tube, input and output circuits for said tube, a resistance in the input circuit, a resistance in the screen grid circuit of said tube, means for effecting flow of direct current through said second resistance to maintain the screen positively biased with respect to the cathode of the tube and a volume control element adjustable simultaneously to vary in the same senses the effective magnitudes of said resistances cumulatively to effect change in volume reproduction.
- 40 17. The method of controlling the output energy of a vacuum tube amplifier which comprises simultaneously controlling amplification of the tube and the amount of input signal supplied thereto.
- 45 18. The method of controlling the output energy of a vacuum tube amplifier which comprises simultaneously varying the bias potential applied to the input circuit of the tube and the amount of input signal supplied thereto.
- 50 19. In an amplifier system, in combination, a vacuum tube amplifier, resistance means for controlling the bias voltage applied to the signal input grid of said tube, resistance means for controlling the signal input voltage applied thereto, and a single means for adjusting both said control resistance means.
- 55 20. The method of controlling the output energy of an amplifier device incorporating at least one electronic tube, which method consists in reducing the amplifying action of the electronic tube and at the same time reducing the amount of input signal energy applied to the amplifier.
- 60 21. The steps in the method of controlling the output energy of amplifying apparatus which is coupled to a source of signal voltage and which includes at least one amplifying tube which comprise increasing the amplifying action of the tube and simultaneously increasing the coupling between the amplifier device and the source of signal voltage in order to increase the output energy of the amplifier device and decreasing the amplifying action of the tube and simultaneously decreasing the coupling between the amplifier device and the source of signal energy to decrease the output energy of the amplifier device.
- 65 16. Radio receiving apparatus comprising a 65
